POTATO CUTTING AND SORTING MACHINE

Albert Larsen, Stetsonville, Wis., assignor of one-fourth to E. J. Hecker and W. M. Vereks, both of Stetsonville, Wis.

Application November 22, 1940, Serial No. 366,746

3 Claims. (Cl. 146—169)

My invention relates to improvements in machines for cutting and sorting seed potatoes and the like.

Among the objects of the invention are to provide a simply constructed machine of few parts and of duplex type equipped for use by two operatives to quickly and easily cut a large quantity of seed potatoes and sort the same, and which is inexpensive to manufacture and service.

To the accomplishment of the above, and subordinate objects presently appearing, a preferred embodiment of my invention has been illustrated in the accompanying drawings, set forth in detail in the succeeding description, and defined in the claims appended hereto.

In said drawings:

Figure 1 is a view in top plan of the preferred embodiment of my invention,

Figure 2 is a view in side elevation,

Figure 3 is a view in end elevation,

Figure 4 is a view in horizontal section taken on the line 4—4 of Figure 2,

Figure 5 is a view in longitudinal section taken on the line 5—5 of Figure 1,

Figure 6 is a view in perspective of one of the operating shafts, and

Figure 7 is a similar view of one of the deflector blades.

Referring to the drawings by numerals, the illustrated embodiment of my invention includes a base structure of table form having an elongated, rectangular top 2, corner legs 3, and a top supporting frame comprising a pair of side boards 4 and a pair of end boards 5.

A suitably smaller, rectangular, seed supply hopper 6 is centered on the top 2 with the sides 7 thereof parallel with and spaced from the sides of the top 2 and its ends 8 further spaced from the ends of said top. The sides 7 of the hopper 6 arise edgewise from the top 2 and are suitably secured to cleats 9 extending along said top and fixed thereto in any desired manner. The ends 8 of the hopper 6 also arise edgewise from the top 2 and are provided with elongated rectangular discharge apertures 10 extending along the lower edges thereof. A pair of rectangular, closure panels 11 are provided on the outer faces of the ends 8 of said hopper 6 for closing the apertures 10. The closure panels 11 are vertically slidable in end guides 12 on said ends 8 into opening and closing positions, respectively. Any suitable means, not shown, may be provided for holding the panels 11 in elevated, open position. The bottom 13 of the hopper 6 slants downwardly from the transverse center of the

hopper to the top 2 from opposite sides of said center, respectively, to the bottom edges of the ends 8 of the hopper.

A pair of square openings 14, relatively smaller than the hopper 6 are provided in the longitudinal center of the top 2 beneath the opposite ends 8 of the hopper, said openings forming drops for the cut potatoes as will presently more clearly appear. A rectangular, skirt-like guard 15 is suitably secured to the under side of the top 2 in the longitudinal center thereof, and with the opposite ends of which the openings 14 communicate.

A potato guide 16, in the form of an inverted V trough, surmounts the top 2 and extends lengthwise through the bottom of the hopper 6 in the longitudinal center thereof and of said top, said guide having reduced ends 17 extending out of the apertures 10 and spanning the openings 14, respectively, with edges bevelled to the top 2 and terminating in line with the outer side edges of said openings.

A pair of elbow type cutting bars 18 are provided in the longitudinal center of the top 2, at opposite ends 8 of said hopper 6, said bars being centered relative to the openings 14, respectively, and including upstanding cutting portions 19 arising from the outer end edges of said openings, and horizontal portions suitably secured to the ends of the hopper 6 above the discharge apertures 10.

Means are provided for feeding the potatoes against the cutting portions 19 of the cutting bars 18 as follows. A pair of elongated pusher blocks 21 are provided at opposite ends of the top 2, respectively, in advance of the cutting portions 19 of said bars 18, and which are mounted on said top for endwise reciprocation in the longitudinal center of the top toward and from said portions 19 by means of a pair of posts 22 depending from said blocks, respectively, through guide slots 23 in the top 2, said posts being suitably secured to the blocks as by screws 24. The inner ends of the pusher blocks 21 have suitably secured thereon resilient hoods 25 for spanning potatoes to be fed to the cutting portions 19.

Operating means for the pusher blocks 21 are provided comprising a pair of rectangular foot pedals 26 at one side of the base arranged in end to end, opposed relation upon opposite sides of the transverse center of the base to slant downwardly from said center, said pedals having outer ends hinged, as at 27, to lateral extensions 28 of a beam 29 extending along said side of the base and suitably secured to the lower ends of

the legs 3 on said side. A pair of operating rock shafts 30 are journalled in the lower edges of the side boards 4 to extend transversely of the base on the opposite sides of the transverse center of the base, closely adjacent thereto, said shafts having end cranks 31 on the same side of the base as the pedals 26 and which extend toward said center. A pair of upstanding pull bars 32 hinged, as at 33, to the inner ends of the pedals 26, respectively, and pivoted to the cranks 31, respectively, as at 34, operatively connecting said pedals to said shafts. The operating shafts 30 are connected to the pusher blocks 21. For this purpose each shaft 30 is provided with a pair of cranks 35 fast thereon upon opposite sides of the guard 15, respectively and each post 22 has fast on the bottom thereof a transverse bar 36 which slides against the bottom of the top 2 and acts as a keeper retaining the related pusher block 21 flat on the top 2. Pairs of connecting rods 37 extend between the cranks 35 of the shafts 30 and the ends of the bars 36, said rods being pivoted to said cranks 35, as at 38, and hinged to the bars 36, as at 39. A coil spring 40 secured at its ends to arms 41 depending from the operating shafts 30 urges said shafts in a direction such that the posts 22 of pusher blocks 21 are held against the outer ends of the slots 23 by means of the cranks 35, connecting bars 37, and bars 36, whereby the normal position of said blocks is established, together with that of the described operating means, and whereby said shafts 30 are tensioned against operation in the opposite direction by depression of the treads 26.

Beneath the top 2 of the base, a series of suitable open top receptacles 42 are mounted in any suitable manner for removal and replacement from the side of the base opposite that on which the pedals 26 are mounted. Preferably one receptacle 42 is provided in the center of said base and a pair upon opposite sides of the center one and beneath the openings 14. End bails 43 on the receptacles 42 provide for easily replacing and removing the same.

Pivoted, as at 44, in the guard 15, adjacent opposite ends thereof and below the openings 14 is a pair of upstanding deflector blades 45 having upper edges extending upwardly through said openings, said blades being swingable about axes transverse to the top 2 into oppositely inclined positions in which said blades engage the outer and inner end edges of the openings 14 to deflect the cut potatoes into either the side receptacles 42 or into the center one, as desired. A coil spring 48 secured to cranks 51 on the blades 45 yieldingly holds the blades 45 inclined against the inner edges of the openings 14 whereby the cut potatoes are normally deflected into the side receptacles 42. Pull rods 46 pivoted, as at 47, to the blades 45 and slidably extended upwardly through the top 2 by way of openings 49 in the latter, provide for manipulating said deflector blades in opposition to the spring 48 to incline the same against the outer ends of the openings 14 so that the cut potatoes may be deflected into the center receptacle 42. The parts 50 are cleats forming bearing strips for the operating shafts 30 and which need merely be identified in passing.

The operation of the invention will be readily understood. The potatoes are deposited in the hopper 6 for gravity feed down the bottom thereof out of the discharge apertures 10 onto the top 2 at opposite ends of the latter, the po-

tatoes being deflected from the openings 14 by the ends 7 of the guide 16. A pair of operatives stationed at opposite ends of the top 2 may then select the potatoes from said top and place the 5 selected ones in front of the pusher blocks 21 to be fed against the cutting portions 19 of cutting bars 18. By depression of the appropriate 10 pedal 26 the operators may then effect reciprocation of the pusher blocks 21 in opposition to the spring 40 to feed the selected potatoes against said portions 19 and effect selective cutting of the same. The manner in which depression of the pedals 26 effects operation of the pusher blocks 21 from their normal position 15 toward said cutting portions 19 will be manifest from the foregoing description of the operating mechanism. The cut potatoes, or the cuttings, fall through the openings 14 and into the side receptacles 42 or into the center one, according 20 to the position in which the deflector blades 45 have been swung in the manner already described.

The foregoing will, it is believed, suffice to impart a clear understanding of my invention without further explanation.

Manifestly the invention, as described, is susceptible of modification without departing from the inventive concept, and right is herein reserved to such modifications as fall within the scope of the subjoined claims.

What is claimed as new is—

1. Apparatus for cutting and sorting potatoes comprising a base including an elevated top of elongated rectangular form having a pair of discharge drops therein in the longitudinal center thereof and upon opposite sides of the transverse center of the top, a gravity feed supply hopper on said top having a pair of end discharge apertures therein extending beyond opposite sides of said drops, to provide for discharge of potatoes from the hopper onto said top upon opposite sides of said drops, a bottom in said hopper inclining oppositely from the center of the hopper to said apertures, respectively, a pair of cutter bars in advance of said drops, respectively, having upstanding cutting portions in the longitudinal center of the top adjacent the drops, means at opposite ends of said top for feeding potatoes against said cutting portions and over said drops 35 for cutting the same into sections to fall through the drops, a plurality of storage receptacles beneath said top, and manipulative means for deflecting the sections from said openings into selected receptacles.

2. Apparatus for cutting and sorting potatoes comprising a base including an elevated top of elongated rectangular form having a pair of discharge drops therein in the longitudinal center thereof and upon opposite sides of the transverse center of the top, a gravity feed supply hopper on said top having a pair of end discharge apertures therein extending beyond opposite sides of said drops, to provide for discharge of potatoes from the hopper onto said top upon opposite sides of said drops, a bottom in said hopper inclining oppositely from the center of the hopper to said apertures, respectively, a pair of cutter bars in advance of said drops having upstanding cutting portions in the longitudinal center of the top adjacent the drops, means at opposite ends of said top for feeding potatoes against said cutting portions and over said drops for cutting the same into sections to fall through the drops, a plurality of storage receptacles beneath said top, and manipulative means for deflecting the 40 sections from said openings into selected receptacles.

3. Apparatus for cutting and sorting potatoes comprising a base including an elevated top of elongated rectangular form having a pair of discharge drops therein in the longitudinal center thereof and upon opposite sides of the transverse center of the top, a gravity feed supply hopper on said top having a pair of end discharge apertures therein extending beyond opposite sides of said drops, to provide for discharge of potatoes from the hopper onto said top upon opposite sides of said drops, a bottom in said hopper inclining oppositely from the center of the hopper to said apertures, respectively, a pair of cutter bars in advance of said drops having upstanding cutting portions in the longitudinal center of the top adjacent the drops, means at opposite ends of said top for feeding potatoes against said cutting portions and over said drops for cutting the same into sections to fall through the drops, a plurality of storage receptacles beneath said top, and manipulative means for deflecting the 45 sections from said openings into selected receptacles.

4. Apparatus for cutting and sorting potatoes comprising a base including an elevated top of elongated rectangular form having a pair of discharge drops therein in the longitudinal center thereof and upon opposite sides of the transverse center of the top, a gravity feed supply hopper on said top having a pair of end discharge apertures therein extending beyond opposite sides of said drops, to provide for discharge of potatoes from the hopper onto said top upon opposite sides of said drops, a bottom in said hopper inclining oppositely from the center of the hopper to said apertures, respectively, a pair of cutter bars in advance of said drops having upstanding cutting portions in the longitudinal center of the top adjacent the drops, means at opposite ends of said top for feeding potatoes against said cutting portions and over said drops for cutting the same into sections to fall through the drops, a plurality of storage receptacles beneath said top, and manipulative means for deflecting the 50 sections from said openings into selected receptacles.

5. Apparatus for cutting and sorting potatoes comprising a base including an elevated top of elongated rectangular form having a pair of discharge drops therein in the longitudinal center thereof and upon opposite sides of the transverse center of the top, a gravity feed supply hopper on said top having a pair of end discharge apertures therein extending beyond opposite sides of said drops, to provide for discharge of potatoes from the hopper onto said top upon opposite sides of said drops, a bottom in said hopper inclining oppositely from the center of the hopper to said apertures, respectively, a pair of cutter bars in advance of said drops having upstanding cutting portions in the longitudinal center of the top adjacent the drops, means at opposite ends of said top for feeding potatoes against said cutting portions and over said drops for cutting the same into sections to fall through the drops, a plurality of storage receptacles beneath said top, and manipulative means for deflecting the 55 sections from said openings into selected receptacles.

6. Apparatus for cutting and sorting potatoes comprising a base including an elevated top of elongated rectangular form having a pair of discharge drops therein in the longitudinal center thereof and upon opposite sides of the transverse center of the top, a gravity feed supply hopper on said top having a pair of end discharge apertures therein extending beyond opposite sides of said drops, to provide for discharge of potatoes from the hopper onto said top upon opposite sides of said drops, a bottom in said hopper inclining oppositely from the center of the hopper to said apertures, respectively, a pair of cutter bars in advance of said drops having upstanding cutting portions in the longitudinal center of the top adjacent the drops, means at opposite ends of said top for feeding potatoes against said cutting portions and over said drops for cutting the same into sections to fall through the drops, a plurality of storage receptacles beneath said top, and manipulative means for deflecting the 60 sections from said openings into selected receptacles.

7. Apparatus for cutting and sorting potatoes comprising a base including an elevated top of elongated rectangular form having a pair of discharge drops therein in the longitudinal center thereof and upon opposite sides of the transverse center of the top, a gravity feed supply hopper on said top having a pair of end discharge apertures therein extending beyond opposite sides of said drops, to provide for discharge of potatoes from the hopper onto said top upon opposite sides of said drops, a bottom in said hopper inclining oppositely from the center of the hopper to said apertures, respectively, a pair of cutter bars in advance of said drops having upstanding cutting portions in the longitudinal center of the top adjacent the drops, means at opposite ends of said top for feeding potatoes against said cutting portions and over said drops for cutting the same into sections to fall through the drops, a plurality of storage receptacles beneath said top, and manipulative means for deflecting the 65 sections from said openings into selected receptacles.

8. Apparatus for cutting and sorting potatoes comprising a base including an elevated top of elongated rectangular form having a pair of discharge drops therein in the longitudinal center thereof and upon opposite sides of the transverse center of the top, a gravity feed supply hopper on said top having a pair of end discharge apertures therein extending beyond opposite sides of said drops, to provide for discharge of potatoes from the hopper onto said top upon opposite sides of said drops, a bottom in said hopper inclining oppositely from the center of the hopper to said apertures, respectively, a pair of cutter bars in advance of said drops having upstanding cutting portions in the longitudinal center of the top adjacent the drops, means at opposite ends of said top for feeding potatoes against said cutting portions and over said drops for cutting the same into sections to fall through the drops, a plurality of storage receptacles beneath said top, and manipulative means for deflecting the 70 sections from said openings into selected receptacles.

9. Apparatus for cutting and sorting potatoes comprising a base including an elevated top of elongated rectangular form having a pair of discharge drops therein in the longitudinal center thereof and upon opposite sides of the transverse center of the top, a gravity feed supply hopper on said top having a pair of end discharge apertures therein extending beyond opposite sides of said drops, to provide for discharge of potatoes from the hopper onto said top upon opposite sides of said drops, a bottom in said hopper inclining oppositely from the center of the hopper to said apertures, respectively, a pair of cutter bars in advance of said drops having upstanding cutting portions in the longitudinal center of the top adjacent the drops, means at opposite ends of said top for feeding potatoes against said cutting portions and over said drops for cutting the same into sections to fall through the drops, a plurality of storage receptacles beneath said top, and manipulative means for deflecting the 75 sections from said openings into selected receptacles.

sections from said openings into selected receptacles, the first mentioned means comprising a pair of pusher blocks slideable on said top, and a pair of foot pedals operative from opposite ends of the top and operatively connected to said blocks, respectively.

3. Apparatus for cutting and sorting potatoes comprising a base including an elevated top of elongated rectangular form having a pair of discharge drops therein in the longitudinal center thereof and upon opposite sides of the transverse center of the top, a gravity feed supply hopper on said top having a pair of end discharge apertures therein extending beyond opposite sides of said drops to provide for discharge of potatoes from the hopper onto said top upon opposite sides of said drops, a bottom in said hopper in-

clining oppositely from the center of the hopper to said apertures, respectively, a pair of cutter bars in advance of said drops, respectively, having upstanding cutting portions in the longitudinal center of the top adjacent the drops, means at opposite ends of said top for feeding potatoes against said cutting portions and over said drops for cutting the same into sections to fall through the drops, a plurality of storage receptacles beneath said top, and manipulative means for deflecting the sections from said openings into selected receptacles, the second mentioned means comprising a pair of deflector blades pivotally mounted in said drops for swinging movement, and manipulative means for swinging said blades from opposite ends of said top.

ALBERT LARSEN.
